NEW JERSEY, A CORPORATION OF NEW JERSEY.

TYPE-WRITING MACHINE.

932,307.

Specification of Letters Patent. Patented Aug. 24, 1909.

Application filed January 18, 1908. Serial No. 411,031.

To all whom it may concern:

Be it known that I, LEWIS C. MYERS, a citizen of the United States of America, residing in the borough of Brooklyn, city and State of New York, have invented certain Improvements in Type-Writing Machines, of which the following is a specification.

This invention relates primarily to margin clamp or margin roll devices for visible writing machines. Its chief characteristic is that the margin clamps are carried on slides fitted and moving within a longitudinally slotted cylinder disposed below the line of print and adapted to be rocked in bearings to carry the margin clamps away from the platen.

The invention is shown combined with paper feed devices constructed, in general, in accordance with the invention of Edward B. Hess. Special means for rocking the slotted margin clamp support is however my invention.

The organization depicted in the drawings is substantially the same as that shown in the application of Edward B. Hess Ser. No. 405,350, filed November 6, 1907.

In the accompanying drawings: Figure 1 is a transverse section taken immediately inside the right hand end plate of the carriage: Fig. 2, a detail front elevation showing the margin clamps or rolls and the hollow longitudinally slotted shaft which carries them: Fig. 3, a detail perspective view of one end of the hollow slotted shaft: Fig. 4, a cross section therethrough: and Fig. 5, a detached view showing one of the slides by which a margin clamp is carried.

1 is the platen; 2 and 3 front and rear feed rolls carried by a frame 4 and suspended by springs 5; one at each end of the platen, connected at their upper ends to the front ends of rocking arms 6, 7 carried by a rock shaft 11. The arm 6 at the right hand end of the platen has, in its lower edge, a recess with an inclined face coöoperating with a pin 9 in the side of a release lever 10 pivoted at 19. In the normal position shown in the drawings, the forward ends of the arm 6, 7, are raised and the springs 5 maintain the front and rear feed rolls in operative relation to the platen. When the release lever is drawn forward the front ends of the arms 6, 7 are allowed to fall thereby permitting the feed rolls to move away from the platen. 12 is a scale bar that is moved

to the printing point by means of its end supporting arms 13, arms 14, rock shaft 15, arms 16 projecting from the rock shaft and slotted link 17, when the release lever is drawn forward. There is a slot in the link 60 17 that is engaged by a pin 18 in the end of the release lever that extends below the axis 19 of the latter. The foregoing is the general construction of the paper feed device comprised in the invention of Edward B. 65 Hess and disclosed in his before mentioned application.

Extending between the side plates (not shown) of the carriage is a hollow cylinder or shaft 20 provided in its front face with 70 a longitudinal slot 21. At each of its ends is secured a ring 22 having a bearing pin 23 upon which pins the cylinder rocks in suitable bearings in the side plates of the carriage. Fitted in the hollow cylinder are 75 slides 24 that may be made of sheet metal formed into the shape indicated in Figs. 4 and 5; that is to say, each has a cylindrical part 25 fitting within the cylinder and frictionally movable therein, flat abutting parts 80 26 that extend through the slot 21 and are formed with bearings 26 (similar to hinge butts) pivoted in which by means of a pivot pin 27 is a sheet metal plate 28 having or carrying in its upper end a margin clamp or 85 roll 29 and provided between the roll and its bearing with a knob or hand piece 30 by which it may be shifted longitudinally of the cylinder 20. A coiled spring 31 is applied to the pivot pin 27 and by its reaction tends 90 to urge the margin roll against the front face of the platen. It is preferred as indicated in Fig. 1 that the slot 21 shall be below a horizontal plane passing through the axis of the cylinder so that dirt of erasure, etc., will not 95 enter the slot. This affords a cheap and very efficient construction of margin clamps adjustable longitudinally of the platen. Where it is desirable to throw off the margin clamp when the paper feed devices are released, it 100 is only necessary to impart a rocking movement to the cylinder 20. In the construction shown when this rocking movement occurs, the bearings 26 move downwardly and by reason of abutment of the plates 28 against 105 the periphery of the cylinder 20, the margin clamps will be moved away from the face of the platen. This rocking movement may be effected as follows. Adjacent its right hand end cylinder 20 is provided with a vertical 110

2 projection 32 to which at 33 is pinned the front end of a rearwardly extending link 34 whose rear end is pivoted at 35 to a projection 36 extending from the release lever 10 in rear of its axis 19. When the release lever is drawn forward to throw off the paper feed rolls, the forward thrust of link 34 will rock cylinder 20 and throw the margin clamps or rolls out of operation.

10 In normal position link 34 is in line with the axes 33, 35, and therefore acts to lock the parts. When the release lever is operated and axis 35 carried up to the position shown in dotted lines, reaction of spring 37 applied 15 to cylinder 32 is not sufficient to return the parts to normal position.

I claim:

1. In combination with the platen of a visible writing machine, a hollow longitudinally slotted cylinder parallel with the platen, a slide adjustable within the cylinder and having a part extending through the slot thereof and a margin clamp arm pivotally mounted in said part.

25 2. The combination with the platen of a visible writing machine, of a transverse longitudinally slotted rocking cylinder, a slide fitted in the cylinder and adapted to be adjusted longitudinally thereof and having 30 a part extending through the slot, a margin clamp arm hinged in said part and means for rocking the cylinder to move the margin clamp arm away from the platen.

3. In combination with the platen of a 35 visible writing machine, a transversely disposed rocking member disposed below and in front of the platen, a margin clamp arm adjustable longitudinally thereof and having pivotal connection therewith, a projection adjacent one end of said rocking member, a link pivoted thereto and extending rearwardly across the end of the platen and a paper feed release lever to which the link is pivoted, whereby when the release lever is 45 operated to throw off the paper feed, the rocking member is rocked to move the margin clamp arm away from the platen.

4. The combination with the platen of a 50 visible writing machine of a hollow longitudinally slotted cylinder, rings applied to the ends of the cylinder and provided with bearing pins adapted to rock in bearings in the end plates of the carriage and margin clamp supports fitting within the hollow cylinder projecting through the slot thereof and adjustable longitudinally of the cylinder.

5. In combination with the platen of a 55 writing machine, a hollow longitudinally slotted cylinder parallel with the platen, a slide adjustable within the cylinder and having 60 a part extending through the slot thereof

and a margin clamp arm mounted in said part.

6. The combination with the platen of a writing machine, of a transverse longitudinally slotted rocking cylinder, a slide fitted in the cylinder and adapted to be adjusted longitudinally thereof and having a part extending through the slot, a margin clamp arm hinged in said part and means for rocking the cylinder to move the margin clamp arm away from the platen.

65 7. The combination with the platen of a writing machine, of a transverse longitudinally slotted rocking cylinder, a slide fitted in the cylinder and adapted to be adjusted longitudinally thereof and having a part extending through the slot, and terminating as a pressure device against the platen and means for rocking the cylinder to move the 70 margin clamp arm away from the platen.

75 8. In combination with the platen of a writing machine, a transversely disposed rocking member located below and in front of the platen, a margin clamp arm adjustable longitudinally thereof, a projection adjacent one end of said rocking member, a link pivoted thereto and extending across the end of the platen; and a paper feed release lever to which the link is pivoted, whereby when the release lever is operated 80 to throw off the paper feed, the rocking member is rocked to move the margin clamp arm away from the platen.

9. In combination with the platen of a 95 visible writing machine, a transversely disposed rocking member, a margin clamp arm adjustable longitudinally thereof, a projection adjacent one end of said rocking member, a link pivoted thereto and a paper feed release lever to which the link is pivoted, the parts being so related that when in normal position the axis of the link is in line with its points of connection with the release lever and said rocking member.

10. In a writing machine, a transversely disposed rocking member located in front of and below the platen and means for actuating it, a margin clamp and a release lever, 100 means interposed between the rocking member and the release lever for actuating the rocking member, said means serving to hold the rocking member locked against movement when the release lever stands in normal position.

105 In testimony whereof, I have hereunto subscribed my name.
